UNITED STATES PATENT OFFICE.

THOMAS C. DINGMAN, OF CLEVELAND, OHIO, ASSIGNOR TO THE WHITE MOTOR COMPANY, OF CLEVELAND, OHIO, A CORPORATION OF OHIO.

INSTRUMENT PANEL.

Application filed May 27, 1926. Serial No. 112,047.

My invention relates to instrument panels, and a dash light, all of which are more particularly to a panel of a type of the conventional type and suitably adapted to support the various instruments attached to the panel, indicating the operation of the motor in an automotive vehicle.

An object of my invention is to provide a panel wherein the faces of the instruments are artificially illuminated in an improved manner.

10 Another object of my invention is to provide a panel for supporting indicating instruments and to effect the protection of the instruments from such injury as may be inflicted by a blow from an extraneous object.

15 Another object of my invention is to direct the rays of light from an incandescent lamp housed within the panel, to the faces of the instruments, in an improved way.

Another object of my invention is to provide a panel possessing the above advantages, wherein a plurality of instruments may be installed in the panel as a unit, each being similarly illuminated and protected.

Other objects of my invention and the invention itself will be readily apparent from the following description of an embodiment of my invention, and in which description reference will be had to the accompanying drawings, illustrating said embodiment for the purpose of explaining my invention.

Referring to the drawings:

Figure 1, is a front elevation of an instrument board of an automobile with my improved construction embodied therein.

35 Figure 2 is a view showing a section upon a vertical plane at right angles to the instrument board, and the position of which is indicated by the line 2-2, in Figure 1.

Figure 3 is a rear elevation of the panel.

40 Figure 4 is a detail view in perspective of the instrument panel.

Figure 5 is a view in perspective of the casing for the structure illustrated in Figure 4.

45 For the purpose of illustrating the association of the various indicating and controlling instruments with the improved panel embodying my invention, I have shown in Figures 1 and 2, a number of

50 gauges and instruments of the conventional type mounted in the usual manner on the instrument panel 10. The gauges herein shown include a speedometer 11, an oil gauge 12, and an ammeter 13. I have also shown

55 ignition and light switches 14, a choke han-

10, is supported on brackets 17, formed with flanges 18, to facilitate the mounting of the panel and afford a suitable base for securing the brackets to the dash or body of the vehicle.

The portion of the panel that supports the instruments comprises a plate 19, preferably constructed of metal and formed with apertures 20, to accommodate the mounting of the various instruments. The rear face of the plate is provided with bosses or legs 21, having studs 22, screw threaded therein upon which nuts 24, are threaded for securing the plate to the brackets 17. The

upper portion of the plate 19, is formed with a semi-circular depression 25, obliquely disposed with relation to the major portion of the plate and inclined rearwardly therefrom.

Within this portion of the plate there are openings 26 and 27, provided preferably, for mounting gauges whose function is to indicate the operation of the motor units. Above these openings there is a vertically disposed extension 29, of the depressed surface 25, and midway of the width of this extension an aperture 30, is provided for mounting the dash light 16. The extension 29, is angularly disposed to the surface 25, and parallel with the plane of the major portion of the plate 19, as shown in Figure 2.

By thus forming the several portions of the instrument supporting plate it will be seen that the position of the incandescent lamp 31, when mounted in the conventional receptacle, will effectuate the most efficient illumination of the instruments and it will also be seen that by virtue of the depressed surface 25, the dials of the indicating instruments or gauges will be safeguarded from injury by a blow from some extraneous force.

100 The plate 19, is encased in a housing 32, which comprises side walls 33, encompassing the periphery of the plate 19, and inwardly disposed beaded flanges 34, integral with the bottom and side walls of the housing. The housing is supported by the brackets 17, and is secured thereto by bolts 35, which pass through apertures 36, in the flange 18, and aligned apertures 37, in laterally disposed flanges 38, integrally formed

with the side walls of the housing 32. Adjacent the sides of the housing and intermediate the flanges 38, and brackets 17, there is a panel 39, preferably constructed of wood which is provided chiefly for the purpose of concealing the body frame and brackets beneath the cowl.

The upper wall of the housing embraces the extension 29, and is formed with a depending flange 40, extending below the dash light 16, and terminating with a beaded edge 41, parallel to the lower horizontal edge of the housing. The central portion of the flange 40, is arciform in a lateral plane to permit the assembly or removal of the incandescent lamp 31, and the contiguous portions of this wall are rearwardly arcuated and merge with the flanges 34, at the corners of the housing.

20 The foregoing method of associating the housing with the plate 19, not only renders the appearance of the instrument panel more aesthetic but affords the operator of the vehicle protection from the direct rays of the 25 dash lamp. Furthermore the rays of light from the incandescent lamp 31, will be reflected upon the dials of the instruments, thus intensifying the illumination.

Although the foregoing description is necessarily of a detailed character, in order that the invention may be completely set forth, it is to be understood that the specific terminology is not intended to be restrictive or confining, and that various rearrangements of parts and modifications of structural detail may be resorted to without departing from the scope or spirit of the invention as herein claimed.

I claim—

40 1. In an instrument panel of the class described, an instrument supporting member comprising an apertured plate, the surface of one portion of which is depressed and inclined to the plane of the face of the plate, 45 an instrument having an indicating face supported within said depressed surface, an electric lamp in juxtaposition with said instrument and a housing encasing the sides of said plate and freely telescopic thereto, over, of one of the walls of the housing having a forwardly disposed extension encasing the said electric lamp.

2. In an instrument panel of the class de-

scribed, an instrument supporting member comprising a plate apertured to receive indicating instruments, brackets for supporting the plate and means for securing the plate to said brackets and spacing it therefrom, said plate having a depressed surface in one portion obliquely disposed and rearwardly inclined to the face of the plate, an instrument having an indicating face supported within the said depressed surface, an electric lamp in juxtaposition with said instrument, a housing encasing the sides of said plate and a forwardly disposed extension of one of the walls of the housing enclosing the said electric lamp.

3. In an instrument panel of the class described, an instrument supporting member comprising an apertured plate, the surface of one portion of which is depressed and inclined to the plane of the face of the plate, an instrument having an indicating face supported within the said depressed surface, an electric lamp above said instrument and a housing for the plate and instrument encompassing the sides of the plate and the instrument and extending forwardly beyond the marginal edges of the plate forward face, said housing being formed with a flange depending from a forwardly disposed extension of its upper wall to shield the said electric lamp from being struck by extraneous objects.

4. In an instrument panel of the class described, an instrument supporting member comprising an apertured plate, the surface of one portion of which is depressed and inclined to the plane of the face of the plate, an extension of said depressed surface being angularly disposed therefrom, an instrument having an indicating face supported by the said depressed surface, an electric lamp within said extension above laterally of the instrument, and a housing having side walls telescoped over the plate with its side walls adjacent the marginal edges thereof, said housing having a flange portion depending from a forwardly disposed portion of its upper side wall adapted to shield the lamp from contact with extraneous objects.

In testimony whereof I hereunto affix my signature this 20th day of May, 1926.

THOMAS C. DINGMAN.
